GEORGE C. CRANSTON, OF SOUTH BEND, INDIANA.

Letters Patent No. 88,140, dated March 23, 1869.

IMPROVEMENT IN LAMP FOR DESTROYING INSECTS.

The Schedule referred to in these Letters Patent and making part of the same.

To all whom it may concern:

Be it known that I, GEORGE C. CRANSTON, of South Bend, in the county of St. Joseph, and State of Indiana, have invented certain new and useful Improvements in Lamps for Destroying Insects that assail fruit-trees; and I do hereby declare that the following is a full, clear, and exact description thereof, reference being had to the accompanying drawings, and to the letters of reference marked thereon, which form a part of this specification, in which—

Figure 1 is a vertical longitudinal section.

My invention relates to a novel device for destroying insects, more especially for such as infest trees; and, to this end,

It consists in the employment of a lamp, when constructed and arranged in the manner hereinafter set forth.

To enable others skilled in the art to which my invention appertains, to make and use the same, I will now describe its construction and operation.

In the accompanying drawing,

A represents a circular tin vessel, the sides of which may be one or more inches in height.

B is a receptacle for the oil, or such other material as may be used for giving light.

This receptacle is furnished with wick-tube C, which may be divided in several wick-chambers, for the purpose of diffusing as much light as possible when my device is in actual use.

b b represent two pieces of metal, bent at right angles, and secured to the bottom of vessel A, at or near its centre, so as to form a recess; or groove, as shown in the drawing.

The lower portion, or foot of lamp, or receptacle B,

is provided with projecting sides, or flanges, and so arranged as to slide in grooves just mentioned.

The vessel A is supplied with a suitable bail, D, by which it is suspended in the branch of a tree.

The manner of using my device is as follows:

The lamp B is supplied with oil or other suitable material, and the tube C with the necessary wick.

The vessel A is now supplied with water, which may be made attractive by placing therein a condiment.

The lamp is now lighted, and, by means of bail D, the vessel is suspended in a tree.

The insects, being attracted by the light, will flutter around, or attempt to reach it by crawling. In either event, they fall into the water and are drowned.

I am aware that my device bears some analogy to lamps in ordinary use, but it will be readily observed that the construction and general arrangement of it are such as to make it applicable, not only to ordinary home-purposes, but also to that for which I particularly design it, that of destroying insects.

Having thus described my invention,

What I claim, and desire to secure by Letters Patent, is—

The vessel A, constructed with deep sides, and provided with grooves b b, in combination with the adjustable lamp B and bail D, all arranged as and for the purpose described.

In testimony that I claim the foregoing as my own, I affix my signature, in presence of two witnesses.

GEORGE C. CRANSTON. [L. s.]
